Des. 239,944
Patented May 18, 1976

239,944

INSULATOR FOR BATTERY TERMINALS CONNECTOR

Henry E. Jensen, Lafayette Hill, and Franz M. Wagner,
Lansdale, Pa., assignors to Eltra Corporation, Toledo,
Ohio

Filed Dec. 12, 1974, Ser. No. 532,136

Term of patent 14 years

Int. Cl. D13—99

U.S. Cl. D26—1 A

Fig. 1

Fig. 2

Fig. 3

FIG. 1 is a perspective view of an insulator for battery terminals connector showing our new design;

FIG. 2 is a side elevational view of FIG. 1;

FIG. 3 is a top plan view of FIG. 1;

FIG. 4 is a perspective view of a modified form of the insulator for battery terminals connector shown in FIG. 1;

FIG. 5 is a side elevational view of FIG. 4; and

FIG. 6 is a top plan view of FIG. 4.

We claim:

The ornamental design for an insulator for battery terminals connector, as shown and described.
